BALANCED BURNISHING WHEEL FOR DISTRIBUTING BURNISHING MATERIALS ON BOOTS AND SHOES

Vito Colangelo, North Collins, N. Y.

Application July 17, 1950, Serial No. 174,328

3 Claims. (Cl. 12—79.5)

1

My invention relates to improvements in burnishing wheels for use in connection with the manufacture and repair of boots and shoes.

Notwithstanding the long recognized desirability of providing a burnishing wheel with a long wearing, somewhat resilient and uninterrupted burnishing surface it has been the usual practice to provide the periphery of the wheel with a band of resilient material, such as felt, and to wrap a sheet of leather or fabric, of greater length than the outer circumference of the felt and greater width than the width of the wheel, about the wheel so that its ends overlap and its extended sides may be secured to the sides of the wheel.

The cost and difficulty of forming and securing a piece of leather of sufficient thickness to wear well and the objectionable offset at its overlapping end has militated against the use of such a leather covering for burnishing wheels.

At the present time it is the almost universal practice to use a fabric covering, such as canvas, and to secure the covering to the wheel in the above described manner.

An objection to fabric coverings and the method of securing them to a wheel is that, due to the surface speed of the wheel being about 1200 feet per minute and the offset at the overlapped end of the fabric, the wheel vibrates rapidly in use and causes a pounding effect which greatly shortens the useable life of the fabric and appreciably increases the time required to obtain the desired quality of burnishing.

In a burnishing operation a hard wax is applied to the fabric burnishing surface of the wheel and then the boot or shoe is held firmly against the waxed surface until the heat generated by friction causes the wax to soften and melt, whereupon the wax is transferred to the boot or shoe and, by suitable movements, certain of its surfaces may be waxed and burnished. Other objections to fabric covered wheels are that the fabric absorbs some of the melted wax, thus requiring the use of more wax than necessary for each burnishing operation, and that the heat generated in the wheel during the burnishing operation together with the action of the absorbed wax causes deterioration of the fabric which after relatively short periods of use must be replaced.

The object of my invention is to overcome the objections to prior burnishing wheels by providing a burnishing wheel which by reason of its construction makes it possible to use a thick, tough, long wearing burnishing material having

2

a smooth concentric burnishing surface, which readily transfers the burnishing wax with a minimum of absorption, and which reduces the time and expense involved in burnishing boots and shoes.

My invention resides in the manner of skiving and arranging the end portions of an inner resilient strip and an outer thick, tough and flexible leather burnishing strip, securing the resilient strip to the periphery of a hub and its overlapping skived end portions together, whereby the outer surface of the resilient strip is concentric with the axis of the hub and securing the leather strip to the resilient strip and its overlapping skived end portions together and in a diametrically opposed relation to the skived ends of the resilient strip, whereby the outer burnishing surface of the leather strip is concentric with the axis of the wheel, the resilience of the wheel is substantially uniform and the weight of the securing means in the joint between the skived end portions of the inner strip substantially balances the weight of the securing means in the joint between the skived end portion of the outer strip so that the wheel is substantially balanced and may be rotated at a suitable speed and used for burnishing operations without appreciable vibration.

In the drawing:

Figure 1 is a front elevational view of my burnishing wheel with a portion broken away and showing the manner of securing the wheel to a rotatable shaft.

Figure 2 is a side view of Figure 1 with portions of the wheel broken away to show the form and arrangement of the cemented joints between the skived ends of the flexible and the resilient bands, and

Figures 3 and 4 are perspective views on a smaller scale of the skived strips which form the flexible and the resilient bands.

For the purpose of illustrating the principles of my invention the accompanying drawing shows a burnishing wheel generally designated by the number 10 and having a solid hub 5 formed with a central bore 6 for mounting it on a rotatable shaft 7, with its periphery concentric with the axis of the shaft. An annular flange 8 is secured to each side of the hub 5 by screws 9 and are each secured to the shaft 7 by setscrews 11 for rotation of the wheel by the shaft.

A strip of resilient material 12, preferably a strip of felt, having a width slightly greater than the width of the wheel and having a length approximately one-fourth ($\frac{1}{4}$) greater than the periphery of the hub has its end portions 13 and

14 beveled or skived so that when it is stretched by being tightly wrapped around and cemented to the periphery of the hub its sides are substantially flush with the sides of the hub and the overlapping skived end portion 14 coincides with the overlapped skived end portion 13, and when the portions 13 and 14 are cemented together the hub is provided with a resilient band 12' the periphery of which is concentric with the axis of the hub.

A strip of thick, tough and flexible leather 15, preferably "Buckskin", having a width slightly greater than the width of the wheel and having a length approximately one-fourth ($\frac{1}{4}$) greater than the periphery of the hub, has its end portions 16 and 17 beveled or skived so that when it is stretched by being tightly drawn around and cemented to the periphery of the felt band, its sides are substantially flush with the sides of the felt and the overlapping skived end portion 17 coincides with the overlapped skived end portion 16, and when the portions 16 and 17 are cemented together the wheel 10 is completely formed. The wheel 10 is thus provided with a resiliently mounted thick, tough and flexible "Buckskin" band 15' the outer surface of which is concentric with the axis of the wheel. The bands and their joints are preferably secured together by a flexibly setting cement so that notwithstanding the joints the resilience of the wheel is substantially uniform.

The strip 15 is secured to the felt 12 with its smoothly finished dense surface outermost, thereby providing the band 15' with a smooth burnishing surface which does not absorb appreciable amounts of the burnishing wax applied thereto, which facilitates distributing the ink or wax to a boot or shoe during a burnishing operation and which resists wear. The periphery of the hub 5 may be transversely straight, but is preferably crowned transversely and the bands 12' and 15' are likewise crowned so that the crowned burnishing surface may be used to quickly and effectively wax and burnish concave as well as plane surfaces.

As viewed in Figure 2 the wheel 10 rotates counterclockwise (as indicated by the arrow). The strip 12 is wrapped clockwise around the hub 5 to form the resilient band 12', and the strip 15 is also wrapped clockwise around the band 12' to form the band 15'. Since, as pointed out above, the strips 12 and 15 are about $\frac{1}{4}$ longer than the periphery of the hub, their cemented joints 18 and 19 respectively are also equal to about $\frac{1}{4}$ of the periphery of the hub. The long flexibly cemented joints provide against sudden changes in the resilience of the burnishing wheel and the resultant pounding effect which would tend to loosen the cemented joints and shorten the life of the wheel. By wrapping the strip 15 counter to the rotation of the wheel the joint 19 is arranged so that any tendency of the work to loosen the overlapping end of the joint is overcome.

In order to balance the slight but appreciable weight of the cement in the inner joint 18 and the outer joint 19 they are arranged diametrically opposite to each other. And to further contribute to the balance of the wheel the strip 12 is skived so that the joint 18, because it is closer to the axis of rotation than the joint 19, is longer and due to the greater amount of cement absorbed by the porous strip at its joint the joint 18 substantially balances the joint 19. The inherent static and dynamic balance of a burnishing wheel so

constructed is such that the wheel may be rotated at a speed suitable for quickly and effectively burnishing boots and shoes. In use the virtual absence of vibration and pounding of my balanced burnishing wheel together with its thick, tough and resiliently mounted long-wearing flexible covering, which readily distributes the burnishing wax with a minimum of absorption, results in reducing the time and expense of burnishing operations in the manufacture and repair of boots and shoes.

Having now described and illustrated one form of my invention, I wish it to be understood that my invention is not to be limited to the specific form or arrangement of parts herein described and shown, or specifically covered by my claims:

I claim:

1. A balanced burnishing wheel for distributing burnishing material on boots and shoes, comprising a hub having a central bore for concentrically mounting the hub on a rotatable shaft; a resilient band of substantially greater length than the periphery of the hub, said resilient band having its inner surface resiliently cemented upon the periphery of the hub with its side edges substantially flush with the side edges of the hub and having its overlapping ends skived and resiliently cemented together, whereby the entire outer surface of said band is concentric with the periphery of the hub; and a band of flexible leather of substantially greater length than the periphery of the resilient band, said leather band having a smooth dense outer surface and having its inner surface resiliently cemented upon the outer surface of the resilient band with its side edges substantially flush with the side edges of the resilient band and having its overlapping ends skived and resiliently cemented together, whereby the entire smooth outer surface of the leather band is concentric with the resilient band and the resilience of the wheel is substantially uniform, said skived and cemented joints being arranged diametrically opposite one to the other, and said inner joint being longer and containing more cement than the outer joint, whereby the weight of the overlapping material and the cement of the longer inner joint balances the weight of the overlapping material and the cement of the shorter outer joint.

2. A balanced burnishing wheel as set forth in claim 1 wherein the lengths of the skived and cemented ends of the leather and the resilient bands are equal to approximately $\frac{1}{4}$ of their peripheries to provide long cemented joints resisting separation in use and promoting the uniform resilience of the wheel.

3. A balanced burnishing wheel as set forth in claim 1 wherein the leather band is relatively thick with respect to its width, whereby its thickness together with its smooth dense outer surface resists penetration of burnishing inks and waxes and their absorption by the resilient band.

VITO COLANGELO.
